PRINTER'S CHASE FOR CHECKS AND THE LIKE

Application filed February 27, 1929. Serial No. 343,068.

This invention relates to a printer's chase for checks and the like.

It is a familiar fact that check blanks or check forms are often assembled in books including stubs and three check blanks or check forms united with each other and with the stubs along perforated lines. These check blanks or check forms are printed nearly always including a date line, a line for the name of the payee and a line for the amount. Appropriate data is printed in proper relationship to these lines and usually the name of the drawer of the check is printed somewhere on the face of the check blanks or forms. So, too, the stub has printed thereon matter identifying the respective checks.

Our invention comprises a chase designed and adapted for use in mounting the type to print these check forms and stubs successively so that when the respective checks are printed the printing will necessarily and essentially be placed and located uniformly on the respective checks, although the three checks of each page or sheet of checks are printed successively and not concurrently. Heretofore difficulty has been encountered in obtaining uniform results and in locating the printing properly and uniformly upon the checks when the pages were run successively through the press. To obviate these difficulties we have produced the present invention and have used the same for a sufficient length of time to ascertain that, by this invention we are able to reduce to a comparatively small amount the cost and expense of printing the checks, and at the same time obtain better and more uniform results. We have searched the market in vain for a chase or device that could be used satisfactorily for these purposes and which would obtain results and benefits approximating the results and benefits which we have obtained by this invention. Therefore, we say, as a result of long and practical experience, that the present invention meets a need and serves a purpose satisfactorily that no other device which we have been able to find will serve.

Fig. 1 is a perspective view of the main chase in which the secondary chase is mounted in different adjusted positions for

printing the lower, the middle and the upper checks successively when the pages are run through the press successively.

Fig. 2 is a perspective view of the secondary chase. 55

Fig. 3 is a perspective view of the main chase and the secondary chase mounted therein showing the manner of their cooperation.

The main chase is in the form of an open frame designed and adapted to be located in the printing press and to be held in the press by usual retaining devices. The main chase frame comprises a lower member 1, an upper member 2 which is parallel with the member 1, and two end members 3 which are parallel with each other and which integrally connect the ends of the lower and upper end members 1 and 2. The inner edge of each of the end members 3 is formed with a series of notches 4. A series of three latch buttons 5 is pivoted to each of the end members 3 adjacent to a series of lugs or projections 6 rigid with the front sides of the end members 3. 60

The secondary or type-holding chase is in the form of an open frame comprising a lower side member 7, an upper side member 8 parallel with said member 7, and two end members 9 that are parallel with each other and which are integrally connected with the members 7 and 8. Each end of the lower side member 7 is extended to provide a projection 10 designed and adapted to be received in the respective notches 4 so as to support the secondary chase in its different adjusted positions in the main chase. 65

In use, the type is set within the secondary chase so as to print one check of a page of checks and the corresponding portion of the stub. The secondary or type-holding chase is then placed in the main chase, preferably in a position in which it is adjacent to the lower side of the main chase. The projections 10 are seated in the lower notches 4 and the sides of the end members 10 fit closely against the inner edges of the frame members 3 of the main chase. The pivoted retainers or buttons 5 are then turned inwardly to the positions shown in Fig. 3 so that said buttons 70 75 80 85 90 95 100

are supported in inclined positions by the projections 6. In such positions the ends of the buttons 5 extend across the outer sides of adjacent portions of the type holding or secondary chase so as to hold said type-holding or secondary chase properly located in the main chase. The printing press is then operated until the desired number of check blanks or check forms at the lower edges of the check pages have been printed. Then the secondary or type-holding chase is removed and located in a position in which the projections 10 are seated in the next adjacent notches 4, which is a position for printing the middle checks of the pages of the checks. The press is then run until the desired amount of work is performed, after which the type-holding or secondary chase is removed and located in its upper position in which the projections 10 are engaged in the upper notches 4. The buttons 6 hold the secondary chase in its various adjustments during operation of the machine.

From the foregoing it must be apparent that our invention is a highly simplified, satisfactory and efficient chase for economically, accurately and rapidly performing the specific type of work mentioned. It is possible that the invention may be varied in some respects and we do not restrict ourselves in any unessential particulars.

We claim:—

1. A printer's chase comprising a main frame having notches in the inner edges of its ends, a secondary frame arranged to be supported in different adjusted positions in the main frame, projections from the ends of the secondary frame arranged to seat in said notches respectively and to support said secondary frame in different adjusted positions in the main frame, and pivoted holders on the main frame movable to position to overlap adjacent portions of the secondary frame.

2. A printer's chase comprising a main frame adapted to be locked in a press bed and having a series of notches in the inner edges of its ends communicating with the top of the frame, a secondary frame adapted to be supported within the main frame and inserted in and removed from the top of the main frame, projections from the ends of the secondary frame adapted to seat selectively in said notches, and pivoted holders on the top of the main frame movable to position to overlap adjacent portions of the secondary frame.
